UNITED STATES PATENT OFFICE.

CARL L. GROHMAN, OF HARTFORD, CONNECTICUT, ASSIGNOR TO PRATT & WHITNEY.
COMPANY, OF HARTFORD, CONNECTICUT, A CORPORATION OF NEW JERSEY.

VARIABLE-SPEED MECHANISM.

No. 927,525.

Specification of Letters Patent. Patented July 13, 1909.

Application filed December 7, 1908. Serial No. 486,274.

To all whom it may concern:

Be it known that I, CARL L. GROHMAN, a citizen of the United States, residing at Hartford, in the county of Hartford and 5 State of Connecticut, have invented certain new and useful Improvements in Variable-Speed Mechanism, of which the following is a specification.

This invention relates to variable speed 10 mechanism.

Variable speed mechanism embodying my invention can be advantageously put to many different uses; for instance in conjunction with or as a part of a grinding-machine, 15 a metal-working machine or a wood-working machine, these being only three specific examples of the different connections in which said mechanism may be employed. As a part of the mechanism is a rocker and it is 20 one of the objects of the invention to so mount and construct this rocker that it shall be stable and that there shall be no possibility of straining the same when manipulated to effect a change in speed. This rocker or 25 carrier presents an advantageous support for a gear element and also for a shifting device for said gear element said shifting device being also substantially supported and in the 30 present case said rocker and shifting device are operated by a handle common to them both.

In the drawings accompanying and forming part of the present specification I illustrate in detail one simple and effective form 35 of embodiment of the invention which to enable those skilled in the art to practice said invention will be fully disclosed in the following description while the novelty of the invention will be included in the claims succeeding said description.

Referring to said drawings, Figure 1 is a front elevation of variable speed mechanism comprising my invention. Fig. 2 is a vertical sectional view of the same. Fig. 3 is a section on the line 3—3 of Fig. 2. Fig. 4 is a detail view of a shifting device as seen from the top thereof, and, Fig. 5 is a sectional side elevation of the forward end of said shifting device the section being on the line 5—5, 50 Fig. 4.

The several figures of the drawings are on different scales and in the same like characters refer to like parts.

The framework for supporting the different 55 parts of the apparatus may be of any suitable

nature the particular construction thereof depending upon the type of machine in which said apparatus is incorporated. The framework shown is in the form of a hollow column or upright 2 which incases and thereby protects the principal elements of the mechanism. I have not shown the column for its complete height, only the intermediate portion thereof being illustrated.

Preferably the primary or main driving 65 element of the mechanism consists of a gear as 3 said gear being of barrel form or consisting of an elongated pinion represented as keyed to the main shaft 4 represented as rotatively supported by bushings as 5 set in the 70 opposite sides of the column 2. Power may be applied to said main shaft in any desirable manner no means for this purpose being shown as the same does not concern the present invention.

The shaft 4 serves as a support or pivot for a yoke such as that denoted in a general way by 6 although said yoke does not turn directly around said shaft being sustained by the bushings 5 to which I have referred. It 80 is not essential even that said shaft support said yoke although it is preferable that the yoke turn about the same axis as that of said shaft whether the latter be rotative or not. It will be therefore apparent that in the present case said rocker or yoke swings or turns about a fixed axis which is advantageous though not essential. The yoke 6 is represented as made up of two sides 7 and 8 and a connecting member 9 shown as located at the 90 rear of the column 2. This cross or connecting member 9 is shown as of segmental or semi-circular form in cross section by virtue of which it acts as a guard for said barrel pinion 3. The lever like yoke or rocker 6 is located within the column 2 and its side arms or branches preferably bear against the inner faces of the side walls of said column by reason of which it will be apparent that said rocker or yoke has no lateral motion which is 100 its preferable relation although I do not restrict myself in this respect. In the present case the yoke or rocker has only a swinging motion and it presents part of the means whereby changes in speed are effected.

In a speed changing mechanism with which I am familiar there is a swinging lever or rocker which is supported by a shaft for such swinging motion and said lever or rocker also has a lateral or transverse movement. In a lever 105

thus mounted it is essential that the same be provided with a very long bearing to withstand the strain of the side motion thereof. As I state I support my rocker preferably 5 for rocking motion only and in this manner avoid the use of such a long bearing. My rocker or lever sustains a gear element or equivalent device and it is necessary that this gear element or its analogous part be 10 shifted transversely of my said rocker or lever. This action in the present case, however, is not obtained by the lateral motion of my lever but by a separate part as will hereinafter appear.

15 The shaft 10 in addition to serving as a strut or tie element also constitutes in the present instance a support for a gear as 12 which is preferably at all times in mesh with the barrel pinion 3. This gear 12 serves as a 20 suitable power-transferring element, for applying the effect of said barrel pinion to any one of the sections or portions of a cone gear as 13 the latter presenting a suitable type of driven member while the barrel pinion presents a suitable type of driving member the pinion 12 being intermediate the two. The cone gear 13 is shown as carried by a shaft 14 supported by the column 2 and it may be 25 loose on said shaft or keyed thereto as occasion may require or particular conditions of use demand this point not being a matter of consequence.

The gear 12 is movable into position to engage the respective sections of the cone gear 30 13 by a compound motion participated in by a rocker or lever such as that described and also by a suitable member supported by said rocker which member may consist of a slide as 15 and which preferably shifts the gear 12 bodily and laterally of said rocker. The slide 15 is shown as supported by the forward shaft 11 its movement thereon being sufficient to put the gear 12 into mesh with any 35 of the sections of said cone gear 13. From the sleeve-like body of said slide 15 there is shown as extending rearwardly or inwardly an arm 16 which preferably has a sliding connection with the shaft 10. In the present case the operator or attendant of the machine grasps the slide 15 of a part thereof to rock or oscillate the rocker 6 and to also shift 40 said slide on said rocker as occasion may require. This particular relation is not essential although I prefer to employ a handle or 45 similar part common to both the rocker and slide or similar elements of whatever nature they may be. Owing to the fact that the slide has a connection with the rocker at the rear of the point of support thereof there is 50 no possibility of the slide being blocked or binding when shifting power is applied thereto. On the arm 16 I have shown a slight projection 17 while from the body of said slide there projects an arm 18 coöperative 55 with said projection the two parts presenting

in effect a fork and receiving between them freely the intermediate gear 12. By the rocking or swinging of the rocker 6 and the simultaneous lateral motion of the slide 15 I may put the gear 12 into mesh with any one 76 of the sections of the cone gear 13 and this operation can be accomplished with ease and facility. All the parts are thoroughly braced and strengthened and the possibility of straining or distorting any of them is practically eliminated although I retain a comparatively long leverage.

Means are preferably provided for positively holding the yoke 6 in an adjusted position and the same are preferably though not necessarily, directly associated with the slide 15 as will now appear. The slide 15 is shown as provided with a curved extension 19 projecting through a diagonally-disposed slot 20 in the front of the column. Said extension is represented as terminating in a barrel or sleeve 21 which slidably receives a plunger as 23 represented as equipped with an operating head 24 for retracting said plunger against the advancing action of a spring as 25 which at all times tends to thrust said plunger forward. The inner end of the plunger is shown as having a socket or seat 26 to receive any one of the four studs or projections extending forwardly from the 95 outside of the front of the column 2. These studs or projections are shown as being located beneath the slot 20 and as also diagonally disposed similarly to said slot. The socket 26 is adapted to interchangeably receive the pins or studs 27, the lowermost of said pins fitting in said socket in Figs. 1 and 2 at which time the gear 12 will be in mesh with the section of least diameter of the cone gear 13, the consequence being that the said 105 cone gear is driven at its highest speed. To get the next speed which is one grade or degree slower the plunger is disengaged from said lowermost pin by a back pull on the same, the rocker 6 and slide 15 then being so 110 relatively operated that the next higher pin 27 will enter said socket. This can be done to obtain the other two speeds, the next two higher pins or studs 27 being successively brought into action at such times. The 115 plunger 23 also holds the slide 15 in an adjusted position. The sleeve or barrel 21 in addition to serving as a convenient means for receiving the spring plunger 23 also presents a very convenient handle for operating both the yoke 6 and the gear shifting slide 15. I therefore provide a swinging yoke or rocker and a slide thereon for shifting a gear in combination with a handle or analogous device common to both the yoke and slide 120 and in the present instance this handle forms a rigid part of the slide although this is not essential. The advantage of a single handle is clearly apparent. In using the term handle I intend to include thereby various manu- 130

ally operable devices whereby the functions of the rocker and slide to effect changes in speed can be secured by an attendant.

It is conceivable that the sleeve or body portion of the slide 15 might be keyed to the front shaft 11, as a matter of fact said sleeve is non-rotatively connected with said shaft the preferable relation. Owing to the fact that the holding device for maintaining the adjustments of the rocker and slide is carried by a part of said slide which is removably connected with means on the framework, it is clear that were the slide 15 simply keyed to the shaft 11 there would be a tendency, due to gear thrusts and from other causes to turn the sleeve like body of said slide 15 on said shaft 11. In view of the presence of the arm 16 this is not possible. Said arm 16 extends to and has a sliding connection with the shaft 10 so that in practice any tendency to turn the slide on the said front shaft is effectually resisted by the shaft 10 in connection with the inwardly extending arm 16 the latter serving as a substantial anchoring member to prevent oscillation or rocking motion of the slide 15. In view of this condition there is no possibility of the plunger 23 being bent or broken.

What I claim is:

30 1. Variable speed gearing comprising an elongated pinion, a rocker supported for oscillation about the axis of said pinion, a gear in mesh at all times with said pinion, supported for movement transversely of said rocker, a shifting device for said gear also supported for movement transversely of said rocker and thereby, and a handle common to the rocker and shifting device for operating either of them.

40 2. Variable speed mechanism comprising a rotary pinion and its supporting shaft, a rocker supported for oscillation by said shaft, a gear supported by and movable transversely of said rocker and in mesh at all times with said pinion, a slide supported by the rocker for movement transversely thereof and provided with means for shifting said gear, and a handle common to the rocker and slide for moving either of them.

3. Variable speed gearing comprising a 50 rotary pinion, a rocker supported for oscillation about the axis of said pinion and provided with two shafts forward of its center of oscillation, a gear supported for sliding movement by the rear one of said shafts and in mesh at all times with said pinion, a slide for shifting said gear, supported by the forward one of said shafts, and an arm connecting said slide with the rear shaft and having a sliding connection with the latter. 60

4. Variable speed mechanism comprising an elongated pinion, a rocker supported for oscillation about the axis of said pinion, a gear in mesh at all times with said pinion, and a shifting device for the gear supported 65 by said rocker for movement transversely thereof.

5. Variable speed mechanism comprising a barrel pinion, a rocker supported for oscillation about the axis of said pinion, a gear 70 in mesh at all times with said pinion, a shifting device for said gear, supported by and movable transversely of said rocker, and a cone gear the sections of which are adapted to be intermeshed with said first mentioned 75 gear by the joint action of said rocker and shifting device.

6. Variable speed mechanism comprising a rocker, a barrel pinion, said rocker being supported for oscillation about the axis of 80 said pinion, a gear to slide transversely of and on said rocker and in mesh at all times with said barrel pinion, a slide supported by and movable transversely of said rocker for shifting said gear sidewise thereon, a handle 85 common to the rocker and the slide for oscillating the rocker or shifting said slide, and a cone gear the sections of which are adapted to be intermeshed with said first mentioned gear by the joint action of said rocker and 90 slide.

In testimony whereof I affix my signature in presence of two witnesses.

CARL L. GROHMANN.
